[57] ABSTRACT

A cam-operated mechanism wherein frictionless roller bearing means are provided between an eccentric cam member and a reciprocating member driven thereby. The cam and reciprocating member are described in particular application to an embossing press or the like, wherein an eccentrically mounted roller is maintained in contact with a vertically movable stamping plate. Roller bearing means are provided surrounding the eccentric roller and interposed between the roller and the stamping plate, whereby the eccentric roller is free to rotate within the roller bearing means, which bearing means are given a substantially frictionless rocking or rolling motion upon the vertically movable stamping plate.

FRICTIONLESS CAM-OPERATED APPARATUS

BACKGROUND OF THE INVENTION

This invention relates generally to cam movements, and particularly to a mechanism in which an eccentric cam member actuates a reciprocating member in periodic fashion.

In known cam-operated mechanisms of the general character described, an eccentric rotatable cam member generally bears directly upon a reciprocatable follower member, which follower member is normally biased to provide continuous contact with the cam member. Due to the sliding or rubbing contact between the cam and the follower, a considerable amount of work is required merely to overcome the frictional forces there between, and additionally, a considerable wear of the moving parts is experienced.

A typical application of such cam mechanisms resides, for example, in embossing presses and similar devices. Such embossing presses are well known in the art, and may, for example, be used for pressing an embossable material into an embossing die. In a typical known construction of such embossing presses, an eccentric roller defining a cam means, which is rotatable by means of a manual handle or other operating means secured thereto, bears against a stamping plate which is vertically movable and which is biased upwardly by springs or other biasing means to press at all times against the eccentric roller, whereby when the roller is rotated, the eccentric portion thereof will move the stamping plate downwardly to engage and emboss the material.

A major drawback of such known embossing presses is that, since the eccentric roller contacts in sliding manner the upper surface of the stamping plate, there is considerable friction between the eccentric roller and the stamping plate, and hence a considerable amount of torque must be applied to the roller to overcome this friction force. Thus, for example, such embossing machines of known construction generally are required to have extremely long operating handles or levers in order to provide such torque. In addition, this high friction between the eccentric roller and the stamping plate results in extremely rapid wear of the contacting parts, necessitating frequent repairs and/or replacement of the worn parts.

SUMMARY OF THE INVENTION

With the above background in mind, it is therefore an object of the present invention to provide an improved cam-operated mechanism.

Specifically, it is a primary object of this invention to provide such a cam-operated mechanism which substantially eliminates sliding friction between the eccentric cam roller and the reciprocating plate or follower member.

It is a further object of this invention to provide such a mechanism which may be hand-operated and which requires considerably less force to operate as compared with prior known devices.

It is yet a further object of the present invention to provide such a mechanism in which wear of the moving parts is markedly reduced in comparison to known devices.

Still a further object of the present invention is to provide an embossing press or similar device incorporating the novel cam-actuated mechanism.

These, as well as other objects which will become apparent as the description proceeds, are implemented by the inventive device characterized by an eccentric roller which in a preferred embodiment is adapted to be rotated by means of a hand-operated lever. A vertically movable plate is maintained in constant contact with the eccentric roller by means of biasing springs or other biasing means, and roller bearing means are provided surrounding the eccentric roller and interposed between the plate and the eccentric roller for providing rocking movement of the roller bearing means relative to the plate and substantially eliminating sliding friction therebetween.

BRIEF DESCRIPTION OF THE DRAWINGS

The invention itself will be better understood, and additional objects, advantages and features thereof will become apparent, from the following detailed description of a preferred embodiment of the invention, taken in conjunction with the accompanying drawing, in which:

FIG. 1 is a perspective view of a hand-operated embossing device utilizing the cam mechanism of the present invention;

FIG. 2 is an end vertical sectional view through the device of FIG. 1, taken along lines 2-2 of FIG. 3;

FIG. 3 is a front elevational view, partially in section, looking along lines 3-3 of FIG. 2; and

FIG. 4 is an enlarged fragmental view showing the manner in which the operating handle is secured to the eccentric roller.

DETAILED DESCRIPTION OF THE INVENTION

Referring now to the drawings, there is shown in FIG. 1 a preferred embodiment of a hand-operated embossing device incorporating the novel cam mechanism of this invention, comprising a pair of end upright support members 10 and 12, respectively, and a die support member 14 secured therebetween adjacent the bottom thereof by means of set screws or the like 16. The end support members 10 and 12 and the die support member 14 may be formed by any suitable method, such as by casting and/or machining.

A vertically movable stamping plate member 18 extends transversely between the upright support members 10 and 12 and is guided for limited vertical movement therebetween by means of a pair of guide flanges 20 which travel within and are guided by a pair of vertical guide slots or recesses 22 in the interior surfaces of the respective end support members 10 and 12. The stamping plate member 18 is biased upwardly by means of biasing means such as coil springs 24 at the opposite ends thereof, so that the stamping plate member is maintained in continuous contact with the lower surface of an eccentric operating cam roller means, which roller means will be described in greater detail hereunder. The lower ends of the springs 24 abut against stationary stops which may be formed by the upper surfaces of respective stub screws 26 within vertical bores 28. The vertical bores 28 may, for example, form downward extensions of the guide slots 22.

Eccentric rotatable cam roller means, generally designated by reference numeral 30, are provided for effecting intermittent downward movement of the stamping plate member 18 upon rotation of such roller means and thus emboss the embossable material between such stamping plate member and a suitable die supported by

the guide support surface 14. As best seen in FIGS. 2 and 3, the cam roller means 30 include a pair of axially spaced, reduced diameter end bearing portions 32 rotatably journaled by any suitable means, such as by roller bearing means 34, within the respective upright support members 10 and 12 and extending therebetween, adjacent the upper ends thereof. An elongated central eccentric shaft portion, of enlarged diameter with respect to these end bearing portions 32, extends axially between and is rigidly secured to the end bearing portions, and is radially off-set with respect thereto, as is best seen in FIG. 2.

Such central eccentric shaft portion, designated by reference numeral 36, customarily in conventional embossing presses of this general nature contacts the upper surface of the stamping plate member 18, whereby rotation of the cam roller means 30, due to the eccentricity of the central radially off-set portion 36, will move the stamping plate member 18 downwardly to thus emboss the embossable material. In such conventional constructions, it is clear that considerable rubbing or sliding friction will be encountered between the rotating eccentric portion of the cam roller means and the upper surface of the stamping plate, particularly since the upward biasing means such as the springs 24 generally press the stamping plate against the roller means with considerable force. Accordingly, in this invention, novel substantially frictionless means are provided for substantially reducing sliding contact between the eccentric portion 36 of the roller means and the upper surface of the stamping plate means 18. As shown in FIGS. 2 and 3, such means comprise outer rotatable sleeve means 38 surrounding the eccentric shaft portion 36 in concentric relation thereto, the sleeve means 38 being rotatable with respect to such eccentric shaft portion. Additionally, to further reduce the operating friction of the inventive press, frictionless bearing means are provided between the eccentric shaft portion 36 and the outer rotatable sleeve means 38 to provide substantially frictionless rolling contact therebetween; as shown, such bearing means may preferably comprise roller bearing means 40 about the periphery of the eccentric shaft portion 30 and utilizing such eccentric shaft portion as an inner race and the concentric sleeve 38 as an outer race therefor.

The outer concentric rotatable sleeve 38 may be formed as a single sleeve extending the full axial length of the eccentric shaft portion 36; however, preferably and as shown, the sleeve means comprise a plurality of axially aligned sleeve sections which are individually rotatable with respect to one another, to compensate for minor play or non-linearity between the lower surface of the sleeve and the upper surface of the stamping plate means 18. If a plurality of such sleeve segments are provided, then the roller bearing means 40 may likewise comprise a plurality of individual roller bearing segments corresponding to each of the individual rotatable sleeve segments.

Suitable means may be provided for rotating the eccentric roller means comprising the end bearing portions 32 and the central eccentric shaft portion 36, in order to effect downward embossing movement of the stamping plate member 18. In a preferred embodiment of the invention, such means may comprise a manually operated handle means 42 non-rotatably secured to one of the end bearing portions 32, whereby rotation of the handle will thus rotate the cam roller means

therewith. As perhaps best seen in FIG. 4, the handle means 42 may, for example, be keyed to the end bearing portion 32 by means of a non-circular slot 44 in the handle means cooperating with a similar non-circular projection 46 on the end bearing portion 32, and the handle may then be secured to such extension by means of suitable securing means such as a screw 48. Suitable stop means, such as an abutment member 50 secured to the appropriate upright support member 10, 10 may be provided for limiting the amount of rotation of the handle 42 and hence the degree of upward and downward travel of the stamping plate member 18.

While the operating means for the eccentric cam roller means has been shown as comprising a manual handle, it should be understood that the invention contemplates the use of any equivalent operating means, as, for example, motor means driving the roller intermittently or continuously through a suitable gear train or through an oscillating crank drive.

It will be appreciated that, inasmuch as the sleeve member 38 surrounding the eccentric shaft portion 36 is free to rotate relative to such eccentric shaft portion 36, the sleeve portion 38 will remain, from a rotational point of view, substantially motionless relative to the stamping plate member 18, while the eccentric shaft portion 36 rotates therein. Thus, as opposed to the high degree of friction encountered in previous known embossing presses of this character, where the eccentric cam roller directly contacted the stamping plate member, only a rocking type of motion is encountered between the outer sleeve member 38 and the upper surface of the stamping plate member 18. Additionally, due to the provision of the roller bearing means 40 between such outer sleeve 38 and the eccentric shaft portion 36, as well as the roller bearing means 34 between the end bearing portions 32 and the end support members 10 and 12, substantially frictionless rotation is achieved between the cam roller and the outer shaft member. Accordingly, it should be therefore appreciated that a substantially frictionless operation of the device is achieved and accordingly, considerably less operating force is required to achieve a given downward force of the stamping plate member 18. Thus, for example, the length of a manual operating handle such as the handle 42 shown, may be considerably shortened and less torque is required to rotate the eccentric cam roller means. Further, due to such reduced friction, it should also be appreciated that a considerably reduced wear of the relatively moving parts is achieved, resulting in a considerably increased life of the device and hence a reduction in the cost of replacement parts and repair.

While the invention has been described as particularly regarding an embossing press embodying the novel cam-operated means, it should be understood that such cam-operated means may find utility in any application wherein it is desired to operate a reciprocating or otherwise periodically moving follower member by means of an eccentric cam means. Thus, for example, the cam-operated means of this invention may be utilized to operate tappet-valves in internal-combustion engines, punch presses, cam-operated clamps and other holding devices, tabletting machines and similar measuring machines, or any other suitable application.

Through the provision of an embossing device as described above, it is believed clear that all of the objects

set forth at the outset to the specification have been successfully fulfilled. ACCORDINGLY,

What is claimed is:

1. Apparatus comprising a pair of parallel spaced apart support members, a longitudinal plate member extending between the support members, means forming cooperating surfaces on the plate member and on the support members for guiding the plate member for reciprocating movement in a straight line substantially at right angles to the longitudinal axis of the plate member, eccentric cam means for effecting reciprocating movement of said plate member, said cam means including a cam roller, means journaling the cam roller at said support members for rotation about an axis substantially parallel to the longitudinal axis of the plate member, said cam means extending from one to the other of said support members and bearing on said plate member at a number of locations distributed along the length of the plate between the support members, biasing means maintaining said plate member in continuous contact with said cam means, and anti-friction means disposed between said cam means and said plate member for providing substantially frictionless contact between the cam means and the plate member at spaced apart locations between the supporting members.

2. An apparatus as defined in claim 1, wherein said last-named means comprises a rotatable sleeve surrounding said eccentric cam roller means and rotatable with respect thereto.

3. An apparatus as defined in claim 2, further comprising substantially frictionless bearing means disposed between said rotatable sleeve and said eccentric cam roller means for providing substantially frictionless rotation of said sleeve means relative to said eccentric cam roller means.

4. An apparatus as defined in claim 3, wherein said

frictionless bearing means comprises roller bearing means.

5. An apparatus as defined in claim 2, further comprising means for effecting rotation of said eccentric cam roller means to thereby effect reciprocating movement of said plate member.

10 6. An apparatus as defined in claim 5, wherein said means for effecting rotation of said eccentric cam roller means comprises a handle means secured to said eccentric cam roller means to effect manual rotation thereof.

15 7. An apparatus as defined in claim 2, wherein the apparatus comprises an embossing press or similar article, further comprising a die support member, said plate member comprising a stamping plate member reciprocable with respect to said die support member to emboss an embossable material therebetween.

20 8. Apparatus as defined in claim 1 wherein said cam means includes sleeve means surrounding the cam roller and the anti-friction means.

9. Apparatus as defined in claim 8 wherein the sleeve means comprises axially aligned sleeve sections which are individually movable with respect to one another.

25 10. Apparatus as defined in claim 9 wherein the anti-friction means comprises sets of roller bearing segments, the respective sets being individual to the respective sleeve segments.

30 11. Apparatus as defined in claim 1 wherein there is a guide support between the support members and spaced from but substantially coextensive with the length of the plate member, said plate member being movable towards and from the guide support, said cam means distributing, along the length of the plate, the pressure exerted by the plate upon work that may be upon the guide support.
